ALEXANDER S. KNOWLES AND CHARLES W. ANDREWS, OF CHICAGO, ILLINOIS, AS-SIGNORS TO TAR & PETROLEUM PROCESS COMPANY, OF CHICAGO, ILLINOIS, A CORPORATION OF ILLINOIS

APPARATUS FOR DISTILLING AND COKING HEAVY HYDROCARBON LIQUIDS

Application filed June 25, 1928. Serial No. 288,183.

This invention relates to a new and improved apparatus for distilling and coking heavy hydrocarbons, and more particularly to an apparatus adapted for the complete distillation and cracking of the volatile constituents and the reduction of the residue to merchantable coke. It is also adapted for use in connection with other liquid hydrocarbons than crude oil.

10 In our prior application Serial No. 227,500, filed October 20, 1927, we have disclosed a method for the treatment of petroleum residues and other heavy hydrocarbons for the distillation of the remaining volatiles and the 15 production of coke. In application Serial No. 218,453, filed September 9, 1927, there is shown an oven suitable for such treatment of heavy hydrocarbons.

We have found that for many purposes it 20 is desirable to introduce the heavy hydrocarbon into our oven or distillation unit at a high temperature. We have also found that unless there are extensive recuperators or other heat recovery devices connected with 25 the heating portion of our ovens, there are considerable heat losses as it is necessary to keep the floors of the ovens at a coking temperature.

In a number of the standard oil treatment 30 and cracking processes, such, for example, as the Jenkins process, the oil is treated in metal containers and it is important to keep the temperature of such containers below a point which would injure the containers or contents. For this reason it is usually necessary 35 to separate the containers from direct contact with the flame by means of refractory walls or partitions. These features involve heat losses and there is the attendant danger 40 of the walls burning away and causing the overheating of the still or the cracking of tubes of the cracking apparatus. This may ruin the contents and destroy the still.

45 It is an object of our present invention to provide a combined apparatus and method whereby the crude oil or the like may be completely treated and the non-volatile residue recovered as merchantable coke.

50 It is an additional object to provide such an

apparatus and method wherein there is a minimum heat loss.

It is also an object to provide a method and apparatus involving a plurality of units such as a preliminary distillation or cracking unit 55 and a final unit for additional distillation and coke production.

It is an additional object to provide such a method and construction whereby the waste heat from the final distillation and coke production unit is utilized in the primary distillation or cracking unit.

Other and further objects will appear as the description proceeds.

We have illustrated somewhat diagrammatically in the single figure comprising the drawing, an apparatus adapted for carrying out our improved method. In the drawing, a usual type of still for use in the Jenkins cracking process is shown at 11. This still is provided with a motor driven propeller 12 which circulates the oil being treated downwardly through the riser 13 to the drum 14. From the drum 14 the oil passes through pipes 15 to the drum 16. From the drum 16 70 the treated oil returns to the body of the still through the riser 17. The pipe 18 leads from the still, through the pump 19, to the distributing pipe 20 in the upper chamber 21 of the oven 22. The pipe is controlled by valve 23. 75 The oven 22 is fully described in our prior applications above referred to.

This oven has a basket 24 or similar device containing crushed coke or the like 25, located in the upper chamber 21. In the main 85 chamber 26 is the rotating basket 27, carried on trunnions 28 and 29. The basket is rotated through power supplied from any desired means to the gear 30. The basket 27 preferably also contains crushed coke. The 90 floor 31 of the oven is preferably formed of refractory material such as hard, dense brick, comprising 60 per cent or more of aluminum oxide. This material has been found to have the required qualities and stand the high heat 95 and the application of liquid at high temperatures without spalling and cracking. The layer of coke 32 is shown as formed upon the floor 31.

The combustion flue 33 is located below 100

the floor 31 and the burner or fuel introduction pipe 34, controlled by valve 35, leads to this flue. The combustion flue 33 is connected to the regenerator flues 36 and 37. 5 The pipe or passage 38, controlled by valve 39, connects the lower regenerator flue 37 with the heating chamber 40 of the Jenkins still 11. The additional passage 41, controlled by valve 42, leads from the combustion flue 33 to the flue 38 at a point beyond the valve 39. The heating chamber 40 of the Jenkins still is enclosed with refractory walls 43 and has an intermediate baffle wall 44 which causes the hot gases to pass upwardly and downwardly through the tubes 15 to reach the flue 45 which carries off the gases.

In the operation of the apparatus crude oil, or other liquid hydrocarbon suitable for 20 treating by the Jenkins or other distillation and cracking process, is introduced into the cracking still 11. It will be understood that while the Jenkins still has been shown, this is merely by way of illustration, and any type 25 of still or cracking apparatus may be used at this point. The liquid hydrocarbon is treated in a mass in such stills at a moderate temperature which normally will run between 600° to 900° F.

30 After the oil has been treated in this still the heavy residue of this treatment is carried through pipe 18 by pump 19 to the distributing pipe 20 in the top of the oven 22. This heavy residue will be at a comparatively 35 high temperature as it comes from the still, which temperature may be from 500° to 600° F. The heated liquid is distributed by pipe 20 over the crushed material in the basket 24 and drops down on to the rotating basket 40. 27. As it passes down through the material in the two baskets an additional distillation takes place and the volatiles are carried off through the upper passage 46. The material is spread in thin films over the coke or other 45 material, causing large surface contact with the ascending volatile gases. This facilitates heat transfer as well as distillation. While still in the liquid form the material drops to the floor 31 which floor is maintained at a 50 coking temperature and the material is coked thereon.

The flues 33 are carried at a high temperature and the products of combustion are passed through pipe 38 to the heating chamber 40 of the primary still or cracking unit. The temperature of the gases passing to the chamber 40 may be controlled by means of valves 39 and 42. Any or all of the gases 55 may be taken direct from the combustion flue 33 by means of passage 41. If it is desired to reduce the temperature somewhat the gases 60 may be taken direct through flue 38 from the regenerator flue 37 by opening valve 39. It will be understood that this showing is diagrammatic in character and that there will

be a plurality of regenerator flues 36 and 37 side by side which will be used alternately for the introduction of air for combustion in the upper flues 33 and for the carrying off of the hot gases and storing of heat received from such gases. 70

By means of the apparatus shown we accomplish a very considerable saving of heat both by utilizing the waste heat from the oven flues in heating the primary distillation unit, and also by introducing the residue into the oven while still hot from the primary process. Such a combination of units utilized according to our method, therefore, accomplishes a complete treatment of crude petroleum or the like with a maximum recovery 75 of the volatiles and solids and with the minimum of heat losses. 80

Our description of our method and of an apparatus for carrying out our method is illustrative only as both method and apparatus are capable of modification and change to 85 meet varying conditions, and we contemplate such variations as come within the spirit and scope of the appended claims. 90

We claim:

1. Apparatus for the treatment of heavy liquid hydrocarbons, comprising a distillation apparatus, means for continuously passing the liquid through the distillation apparatus, a heating chamber for the distillation apparatus, a closed, stationary coking chamber for treating heavy liquid residue from the distillation apparatus, a pipe for passing heated liquid from the distillation apparatus to the coking chamber, heating flues for the coking chamber and a connection for leading waste heating fluid from said flues to said heating chamber. 95

2. Apparatus for the treatment of heavy liquid hydrocarbons, comprising a closed stationary coking chamber, means for passing material through said chamber in thin films, heating flues for said chamber, a distillation apparatus for distilling the liquid hydrocarbon, a heating chamber for said distillation apparatus, means for continuously passing the liquid through said distillation apparatus, means for passing liquid residue from the distillation apparatus to the coking chamber, and a connection between the heating flues of the coking chamber and the heating chamber for leading waste heating fluid from said flues to said heating chamber. 100

Signed at Chicago, Illinois, this 13th day 105 of June, 1928.
